OCCUPANT RETENTION EQUIPMENT FOR ROCKING BED**James R. Grosholz, Wayne, Pa., assignor to Air-Shields, Inc., Hatboro, Pa., a corporation of Delaware****Application June 5, 1957, Serial No. 663,728****5 Claims. (Cl. 128—28)**

This invention relates to rocking bed devices for infants and is particularly concerned with a harness system for positioning and retaining an occupant against shifting under the influence of rocking movements.

Rocking beds of the type with which the present invention is concerned may be used to assist in the breathing process of small infants in cases where faulty breathing is present either due to deficiencies inherent at birth or due to respiratory ailments. The rocking movements of the apparatus induce expansion and contraction of the lungs due to the shifting of the internal organs under the rocking action.

To maintain the infant in proper position on the rocking bed it is an object of the present invention to provide apparatus of a relatively simple nature which will effectively retain the infant and which is adjustable to accommodate occupants of different sizes.

A specific object of the invention is to provide a readily adjustable apparatus which combines to maintain the head of the infant in the selected position and at the same time to prevent shift of the body in an upward direction toward the head of the bed.

How these and other objects and advantages of the invention are attained will be evident from the drawings in which—

Figure 1 shows a side elevational view of rocking bed apparatus incorporating the retention system of the present invention.

Figure 2 is a plan view to an enlarged scale of the rocking bed portion of the apparatus showing in greater detail the retention equipment.

Figure 3 is a sectional view through one of the head positioning members of the retention equipment showing the supporting structure and retention clamp.

The rocking bed member shown in Figure 1 is illustrated generally at 5, supported for rocking movements on a pivot 6 which is mounted in lateral supporting members one of which is illustrated at 7. A depending arm 8 is located inside the support 7 and is connected by a connecting rod 9 to a piston 10 in a cylinder 11. The complete rocking bed with its mechanism is supported on a plate member 12, thereby permitting the complete rocking bed to be moved as a unit, and thus when desired the rocking bed unit may be placed inside a baby incubator as illustrated in Figure 1. In this case the rocking bed plate 12 rests on the upper surface 13 of the lower or equipment unit 14 of the incubator. The complete rocking bed is mounted in place of the normal mattress so that the infant receives the benefits of the rocking motion while it is inside the transparent hood 15 in the conditioned atmosphere.

The amplitude of rocking movement is illustrated in Figure 1 where the upper position of the head portion from the bed unit 5 is shown in dotted outline at 5a, and the lower position at 5b. A rod member 16 is provided with suitable clamping mechanism which permits the rod to be moved either to the full line position shown for holding the bed member 5 when it is not moving or the

2

rod 16 may be swung up out of the way alongside the bed during the rocking operation. The drive of the bed is powered by compressed air or the like which is controlled through suitable valve mechanism such as illustrated at 17 (Figure 2). The valve is suitably controlled with reversing mechanism which delivers the air to the cylinder 11 to cause the rocking motion. The details of the rocking mechanism are not part of the present invention but are shown and described in my co-pending application, U.S. Serial Number 663,772 filed June 5, 1957, and issued October 15, 1958 as Patent 2,855,921.

The rocking bed 5 is equipped with a mattress 18 on which an infant 19, shown in dotted outline in Figure 2, may be placed. To retain the infant in position against either lateral or longitudinal displacement under the rocking action of the bed, co-operative pieces of retention equipment are illustrated. A fabric garment such as the diaper-like device 20 is shown extending around the lower portion of the infant's body in normal diaper fashion. The diaper device is preferably constructed with a wrap around part, the ends of which are shown at 20a and 20b one on top of the other, and an extending part 20c. This latter part is proportioned to extend between the infant's legs and up over the wrap around part. The parts are secured in this position as illustrated. Attached to the lower portion of the diaper fabric underneath the body, is a central strap 21 which extends downwardly to the foot of the bed member 5 where it may be anchored by a quick detachable fastener 21a. Two additional strap members 22 are attached to the upper corners of the diaper device 20 at the sides and each extends diagonally outwardly to the side of the bed 5 where each strap may be attached by a suitable fastener 23. This readily applied garment serves to hold the lower portion of the body against downward movement beyond the desired position and also to some extent restricts lateral motion of the body. However angular movement, particularly of the upper portion of the body, and twisting is not suitably restrained by the diaper and its straps.

In order to restrain the infant against upward and angular movements additional equipment is provided. At each side of the bed 5, in the region opposite the head and shoulders of the infant, a rod support 24 is firmly connected to the bed structure. Supported by these rods 24 are the positioning devices, each of which incorporates a cylindrical member 25, made of resilient material such as sponge rubber which may be brought into contact with the shoulders and cheeks of the infant without causing discomfort.

The supporting structure for the cylindrical member 25 includes a structural core 26 to which is attached the upper flat supporting arm 27. A slot 28 in the outer end of arm 27 provides the opening through which the hand screw connector 29 extends into the block 30. Supporting block 30 is provided with an opening 31 through which the rod support 24 extends. A slot 32 extending from the edge of block 30 to the opening 31 permits deformation under the tightening action of the screw 29 to produce clamping of the block 30 on the rod support 24.

Likewise tightening of the screw 29 by rotation of the hand knob 29a causes the shoulder of the screw to engage the arm 27 and clamp it down tightly against the block 30. Thus the hand screw 29 clamps in one operation both the arm 27 on the block 30 and the block 30 on the rod support 24.

With the hand screw 29 loosened, the block 30 may be slid along the rod support 24 or pivoted with respect to it and at the same time the beam 27 may be slid in or out to the extent of slot 28 and also may be positioned angularly with respect to block 30. This quick acting clamp construction therefore permits the arm 27 to be moved to properly locate each cylindrical member 25 in

the best position for retaining the patient against shifting during movement of the bed.

With this structure the infant's shoulders are prevented from moving upwardly beyond the cylindrical members 25 and the lateral movement of the infant's head is restricted thereby preventing any appreciable angular shift in the position of the infant.

From the foregoing description it will be evident that I have provided relatively simple and effective equipment for maintaining the position of an infant on a rocking bed apparatus. By the use of the diaper-like garment anchored by straps in the general manner described, the lower portion of the infant's body is restrained against undesired shift in position, while still permitting free movement of the legs. The quick attachment fasteners for the anchoring straps allows the diaper device to retain the usual rapid change advantages. The fast acting clamps and the universal adjustment structure supporting the padded cylinders provide highly effective means for safely maintaining the position of the upper portion of the body on the bed device.

I claim:

1. Apparatus for retaining an occupant on a rocking bed including a garment constructed to extend around the lower part of the occupant's body, a strap extending from said garment to the bottom of the bed, attachment means for fastening the end of said strap to the bed, a pair of laterally extending straps attached to the upper part of said garment, said lateral straps having provision for attaching to the sides of said bed and adjustable 30 bracing members attached to the sides of said bed for engaging the shoulders of the occupant to prevent upward shift of position.

2. Apparatus in accordance with claim 1 in which

each resilient member is in the form of a cylindrical element having one end supported on one of said arms.

3. Apparatus in accordance with claim 1 in which the end of each said arms opposite to the resilient member is adjustably supported by means of a clamp block mounted on the bed for longitudinal movement, the arm being supported on said block for sliding movement in a direction generally transverse the bed and a handscrew in said block to clamp both the longitudinal and trans-

verse movements.

4. Apparatus in accordance with claim 1 in which the end of each arm is supported by a clamping screw on a clamp block, a slot in said arm to permit movement of said arm on said block in a generally transverse direction, said block being supported for sliding longitudinal movement at the side of said bed, said clamping screw applying the clamping of the arm to the clamp block and also applying a clamping between the bed and said block.

5. Apparatus in accordance with claim 1 in which the adjustable support for each arm includes a longitudinal rod at the side of the bed, a clamp block slidably and pivotally supported on said rod, a clamp screw in said clamp block, said arm having a slot engaging said clamp screw to provide for sliding and pivotal adjustment with respect thereto, said clamp screw being constructed to clamp the longitudinal and pivotal movement of said block on said rod and to clamp the arm to said block.

UNITED STATES PATENT OFFICE
Certificate of Correction

Patent No. 2,883,981

April 28, 1959

James R. Grosholz

It is hereby certified that error appears in the printed specification of the above numbered patent requiring correction and that the said Letters Patent should read as corrected below.

Column 3, line 34, beginning with "2. Apparatus in accordance" strike out all to and including "block" in column 4, line 28, and insert instead the following, which comprises claims 2, 3, 4, and 5:

2. A rocking bed incorporating apparatus for retaining an occupant thereon including a pair of arms each of which is adjustably supported on said bed in a position adjacent the normal location of the head and shoulders of the occupant, a resilient member attached to the end of each of said arms to engage the shoulders of an occupant to prevent upward shifting and a clamp device to retain each of said arms in adjusted position, each resilient member being in the form of a cylindrical element having one end supported on one of said arms.

3. A rocking bed incorporating apparatus for retaining an occupant thereon including a pair of arms each of which is adjustably supported on said bed in a position adjacent the normal location of the head and shoulders of the occupant, a resilient member attached to the end of each of said arms to engage the shoulders of an occupant to prevent upward shifting and a clamp device to retain each of said arms in adjusted position, the end of each said arms opposite to the resilient member being adjustably supported by means of a clamp block mounted on the bed for longitudinal movement, the arm being supported on said block for sliding movement in a direction generally transverse the bed and a handscrew in said block to clamp both the longitudinal and transverse movements.

4. A rocking bed incorporating apparatus for retaining an occupant thereon including a pair of arms each of which is adjustably supported on said bed in a position adjacent the normal location of the head and shoulders of the occupant, a resilient member attached to the end of each of said arms to engage the shoulders of an occupant to prevent upward shifting and a clamp device to retain each of said arms in adjusted position, the end of each arm being supported by a clamping screw on a clamp block, a slot in said arm to permit movement of said arm on said block in a generally transverse direction, said block being supported for sliding longitudinal movement at the side of said bed, said clamping screw applying the clamping of the arm to the clamp block and also applying a clamping between the bed and said block.

5. A rocking bed incorporating apparatus for retaining an occupant thereon including a pair of arms each of which is adjustably supported on said bed in a position adjacent the normal location of the head and shoulders of the occupant, a resilient member attached to the end of each of said arms to engage the shoulders of an occupant to prevent upward shifting and a clamp device to retain each of said arms in adjusted position, the adjustable support for each arm including a longitudinal rod at the side of the bed, a clamp block slidably and pivotally supported on said rod, a clamp screw in said clamp block, said arm having a slot engaging said clamp screw to provide for sliding and pivotal adjustment with respect thereto, said clamp screw being constructed to clamp the longitudinal and pivotal movement of said block on said rod and to clamp the arm to said block.

Signed and sealed this 8th day of September 1959.
